Patented Aug. 17, 1915.

UNITED STATES PATENT OFFICE.

WILLIAM W. JONES, OF NEW CASTLE, PENNSYLVANIA.

CAR-REPLACER.

1,150,037.

Specification of Letters Patent. Patented Aug. 17, 1915.

Application filed February 2, 1915. Serial No. 5,659.

To all whom it may concern:

Be it known that I, WILLIAM W. JONES, a citizen of the United States, residing at New Castle, in the county of Lawrence and State of Pennsylvania, have invented certain new and useful Improvements in Car-Replacers, of which the following is a specification.

This invention relates to car replacers, and belongs to that class of devices which are placed in position beside railway rails, and, usually secured to the rails temporarily, and which are provided with upwardly inclined surfaces arranged in the path of the wheels of a derailed car and up which the wheels may be drawn and directed upon the rails.

The replacers in present use with which this applicant is acquainted are so constructed that all of the weight of the car is thrown upon the flange of the wheel, causing the replacer to slide from under the wheel when it ascends or starts up; also, causing the replacer to break in the center. The weight of the car or engine often causes the flange to cut a groove in the replacer, thus keeping the wheel from sliding off upon the rail as desired and resulting in considerable extra work and trouble.

It is the object of this invention to produce a replacer having a rib for the tread of the wheel that will allow the flange to ride clear of the bottom of the lead for the flange until the middle portion of the replacer is reached, when the wheel runs off upon the rail without having to slide very much down the slanting surface at the summit of the replacer. The lead for the flange has a vertical wall on both sides of it, and the wheel cannot slide off before reaching the proper position on the replacer to take the rail.

The special construction and arrangements of the parts of this invention are set forth in the accompanying drawings, of which—

Figure 1 represents a cross-section of a railway track with this invention applied on the inside of one rail and the outside of the other rail. Fig. 2 is a top plan view of this invention. Fig. 3 is a bottom plan view. Fig. 4 is a front view. Fig. 5 is a rear view. Fig. 6 is a vertical section on the broken line $x-x$ of Fig. 5. Fig. 7 is a vertical cross-section on the broken line $y-y$ of Fig. 5. Fig. 8 is a top plan view of a modi-

fication of this invention. Fig. 9 is a bottom plan view thereof. Fig. 10 is a rear view of the modification. Fig. 11 is a front view. Fig. 12 is a vertical section on the broken line $x-x$ of Fig. 10. Fig. 13 is a vertical section on the broken line $y-y$ of Fig. 10. Fig. 14 is a top plan view of the hook member used to secure this invention to the rails.

Throughout the description and drawings the same letter is used to refer to the same part.

Considering the drawings, Figs. 1 to 7 inclusively, and Fig. 14, it will be noted that upon a tie A is placed one end of the replacer C. Next to the rail and along one side of the replacer is the rib D for the tread of the wheel. Alongside the rib is the lead E for the flange of the wheel, and the lead has the walls d and e at the sides. The walls extend diagonally toward the rail. At the other end of the replacer there is the rib F, the lead E' with the walls d' and e' at the sides. The rails are lettered B and b.

To secure the replacer to the rail, the hook member G is used. The hook g engages the flange of the rail and the shank or body of the member G passes beneath the rail and the head H is passed through the opening J in the back of the replacer C. The throat h is placed in the recess j leading downwardly from the opening J, and the head H is arranged below the lugs K and L projecting from the back of the replacer C, so that the member G cannot become detached and the replacer cannot move away from the rail sidewise.

Now considering Figs. 8 to 13 of the drawings inclusively, it will be observed that a modification of this invention is illustrated. The rib M for the tread of the wheel is arranged near the other side of the replacer L and has a wall m . The lead N for the flange of the wheel lies alongside the rib as before, and has the side walls n and O, the wall n being the diagonal wall. At the other end of the replacer L the rib P has the wall m' , and the lead Q has the walls n' and R.

Both the form of this invention first herein described, and the modification are double ended replacers, and they have the slanting middle portions f and S , as illustrated best in Figs. 6 and 12.

In the Figs. 8 to 13, it will be seen that this invention has a straight vertical side,

which is the lower side, and that straight walls O and R are arranged at the top of the vertical lower side, and incline upwardly toward the middle and toward each other. Further, the leads N and Q for the flanges of the car wheels are arranged next to the straight walls, and the leads have the walls n and n' extending in a slanting direction toward the straight walls. The flat 10 ribs M and P for the treads of the car wheels are located higher than the surfaces of the leads, and the ribs have the side walls m and m' . As best shown in Fig. 11, all the 15 straight walls, leads, ribs and side walls mentioned, merge at the middle where they reach their highest points into a single, flat, downwardly-inclined surface leading to the lower vertical side, and down which inclined surface the car wheel may slip upon the rail.

20 In the operation of this invention, considering Figs. 7 and 13, the flanges of the wheels in the leads E' and Q do not reach the bottoms of those leads. In using the replacer C, as best set forth in Fig. 6, the 25 flange of the wheel does not touch until the slanting middle portion f has been reached, and the contact is then a sliding one of short duration. In using the modification L, as best shown in Fig. 12, the flange runs off as

the slanting middle portion S is reached 30 and the wheel slides but a very little way until the rail is taken. The diagonal walls of the leads by contact with the flanges direct the wheels to the rails.

Having now described and explained this 35 invention, I claim;

A car replacer, having a straight vertical lower side, straight walls formed at the top of the said vertical side and inclining upwardly toward each other, leads for the 40 flanges of car wheels arranged next to the said straight walls and having side walls extending in a slanting direction toward the said straight walls, flat ribs constructed to receive the treads of car wheels and located 45 higher than the surfaces of the said leads, the said ribs having side walls, and all the said straight walls, leads, ribs and side walls merging together at their highest points into a single flat, downwardly-inclined surface leading to the said vertical lower side. 50

In testimony whereof I affix my signature in presence of two witnesses.

WILLIAM W. JONES.
